Peterson, co-partners, doing business as Vogel-
Peterson Co., Chicago, Ill.

Application May 27, 1942, Serial No. 107,020

Term of patent 3½ years

To all whom it may concern:

Be it known that I, Raymond A. Magnuson, a citizen of the United States, residing at Chicago, in the county of Cook and State of Illinois, have invented a new, original, and ornamental Design for a Garment Rack, of which the following is a specification, reference being had to the accompanying drawing, forming part thereof.

Fig. 2 is a perspective view of the rack as viewed from one end thereof.

I claim:

The ornamental design for a garment rack, substantially as shown.

RAYMOND A. MAGNUSON.
